BOTTLE OPENER

John A. Haberkorn and Michael Petrillo,
Denver, Colo.

Application May 13, 1949, Serial No. 2,619

Term of patent 14 years

(Cl. D44—29)

To all whom it may concern:

Be it known that we, John A. Haberkorn and Michael Petrillo, both citizens of the United States of America, residing at Denver, in the county of Denver and State of Colorado, have invented a new, original, and ornamental Design for Bottle Openers, of which the following is a specification, reference being had to the accompanying drawing, forming part thereof.

In the drawing:

Fig. 1 is a front view of a bottle opener, showing our new design;

Fig. 2 is a top view thereof,

Fig. 3 is an end view thereof; and

Fig. 4 is a perspective view thereof.

We claim:

The ornamental design for a bottle opener, as shown.

JOHN A. HABERKORN.
MICHAEL PETRILLO.
